UNITED STATES PATENT OFFICE

155,289

DESIGN FOR A DRINKING MUG

Warner W. Hoople, Dallas, Tex., assignor to Mildred A. Skelley, Dallas, Tex., doing business as Weber's Root Beer Company

Application August 22, 1947, Serial No. 141,010

Term of patent 7 years

(Cl. D36—8)

To all whom it may concern:

Be it known that I, Warner W. Hoople, a citizen of the United States of America, residing at Dallas, in the county of Dallas and State of Texas, have invented a new, original, and ornamental Design for Drinking Mugs, of which the following is a specification, reference being made to the accompanying drawing, forming a part thereof.

Fig. 1 is a side elevational view of a drinking mug, showing my new design;

Fig. 2 is another side elevational view taken at right angles to Fig. 1;

Fig. 3 is a top plan view; and

Fig. 4 is a bottom plan view thereof.

I claim:

The ornamental design for a drinking mug, as shown.

WARNER W. HOOPLE.
